UNITED STATES PATENT OFFICE.

WALTER B. BALLOU AND HOWARD M. BALLOU, OF NORTH ATTLEBORO, MASSACHUSETTS.

BOTTLE CLOSURE.

Application filed December 28, 1925. Serial No. 77,921.

This invention relates to bottle closures, and is intended to provide a device of this kind which shall be capable of repeated and permanent use on different bottles after the original cork has been removed so that the stopper may be repeatedly removed and replaced with ease without injuring the stopper or impairing its efficiency as a sealing device. At the same time the accumulation 10 of dust or dirt on the edge of the bottle mouth or opening is prevented by an appropriate shield or guard which dispenses with the need of wiping off the edge of the bottle before pouring out liquid. The device is so 15 organized and assembled that the parts are detachable, thereby permitting their use for kindred purposes.

55 60 65 70 75

To this end the invention comprises a sealing stopper or cork element combined with 20 a detachable cover or shield by means of a coupling member, preferably in the form of a cork-screw which, when the parts are assembled, forms a pull member or handle grip removably interlocked with the sealing 25 member, but without impairment or injury to the sealing stopper, while being available for removal of the original cork in the bottle before the permanent bottle closure is inserted.

30 This and other features of the invention will be particularly explained in the following specification, and will be defined in the claims hereto annexed.

In the accompanying drawings:

35 Figure 1 is a side elevation, partly in section, showing the construction and arrangement of the improved bottle closure as it is applied to a bottle whose neck portion is shown in dotted lines.

40 Figure 2 is a bottom end view of the complete device.

Figure 3 is a side elevation showing the shield and sealing stopper in reversed relation to form a measuring or drinking cup.

45 Figures 4, 5, 6 and 7 are detail views showing separate parts forming the stopper element.

In the practice of this invention, according 50 to the form illustrated in the drawings, the stopper element that is insertable into the mouth or neck of the bottle comprises an interior sleeve or tube 1, whose upper end is flared out to form an end flange 1^a, and whose lower end, after the insertion of a

plug 3, of wood or other suitable material, is spun in to form an annular retaining lip or shoulder 1^b. Intermediate of its ends the sleeve is provided with an interior shoulder or ledge 2 which may be formed in any convenient manner for engaging the screw of the coupling member, which forms the means for securing the exterior shield 6 firmly to the interior stopper element. In this case this ledge or shoulder is formed by upsetting a portion of the metal sleeve 1, so as to form a short inwardly projecting tongue 2. The upper end portion of the stopper element comprises a flared thimble 5, whose small end portion is secured to the flared flange 1^a of the sleeve 1, by soldering or in any convenient manner.

55 60 65 70 75 80 85 90 95 100

The shield or dust-protecting cover comprises a bell-shaped or funnel shaped cup 6, whose upper and small end edge is turned inwardly to form a narrow inturned lip 6^a. The interior of the small end of this shield member is shaped to fit snugly over the upper end or thimble member 5 of the stopper so that the lower edge of the shield is correctly positioned around the neck of the bottle and spaced away from the stopper to allow the stopper to be forced tightly into the neck of the bottle.

The peripheral covering layer 1^c of cork fits tightly over the exterior of the sleeve 85 so as to abut snugly against the exterior thimble 5. The lower end of the stopper is sealed by a cap-screw 4, whose cap or head is preferably flared as at 4^a to form a snug seat making a tight joint with the adjacent 90 end of the cork member 1^c, when the screw is screwed tightly into the retaining plug 3, located inside the lower end of the sleeve member 1. It will, therefore, be seen that the cork layer is firmly held between the 95 exterior cap 4^a of the cap-screw and the upper thimble 5 on the sleeve, and the interior bore through the stopper is tightly sealed by the firm engagement between the cap 4^a and the adjacent cork element.

105

The complete stopper shown in the lower part of Figure 3 is firmly seated in the contracted upper end portion of the sleeve 6, and the two parts are held firmly together in proper relation by means of the securing member which, in this case, is preferably in the form of an attaching screw having a handle 7 and a spiral or screw-shank 8, pro-

jected from the boss portion 7^a of the handle and fitting snugly inside the sleeve 1. An annular shoulder 7^b, by its engagement with the inturned end 6^a of the shield, holds the parts firmly together when the shank or screw portion 8 of the pull member is screwed into the stopper by reason of its interlocking engagement with the ledge or shoulder 2 on the sleeve.

10 The handle 7 of the pull member facilitates easy removal of the stopper from the bottle and is itself removable for use as a cork-screw to extract the original cork in the bottle to permit insertion of the permanent sealing stopper with its dust-excluding shield. Since the pull member penetrates only a portion of the cork and does not itself come into engagement with the cork of the stopper, the cork remains unimpaired 15 for further and repeated use since its lower end is permanently sealed by the cap-screw.

Not only is the cork-screw, which forms the pull member of this permanent bottle closure removable for extracting the original cork, but by its removal the funnel or 20 cup-shaped shield 6 may be separated from the sealing stopper for use as a funnel. If desired to use the shield 6 as a measuring or drinking cup its small end may be completely closed by insertion of the cap-screw 25 end which is conveniently made to snugly fit the small end of the shield, as shown in Figure 3, while the stopper, in such case,

forms a handle for the measuring or drinking cup.

It will, therefore, be seen that every part of this assembled closure performs its distinct function in such assembled relation as part of the closure, and is also available for other useful purposes when the parts are dis-assembled.

What we claim is:

1. In a bottle closure, the combination of a stopper element embracing a cork-covered sleeve, a removable funnel shaped shield whose smaller end forms a seat for engaging and supporting the upper end of the stopper, and a cork screw insertable into the sleeve to form interlocking engagement therewith to secure the sealing stopper and shield detachably together while providing a handle for the extraction of the element from a bottle.

2. A bottle closure device embracing stopper, shield, and handle members secured together to form a combined stopper and dust shield telescoping both the interior and the exterior of the bottle-neck and being detachable from each other to permit their separation and reassembling in reversed relation to form a handled measuring cup.

In witness whereof, we have subscribed the above specification.

WALTER B. BALLOU.
